Patented Sept. 17, 1968

212,244

MOTOR-DRIVEN PROPELLING DEVICE FOR TOYS OR SIMILAR ARTICLE

Takaichi Mabuchi, Tokyo, Japan, assignor to Tokyo
Kagaku Kabushikikaisha, Tokyo, Japan, a corpora-
tion of Japan

Filed July 13, 1967, Ser. No. 7,785

Term of patent 14 years

(Cl. D34—15)

FIG. 1

FIG. 2

Fig. 3

Fig. 4

FIG. 5

FIG. 6

FIGURE 1 is a front elevational view of the motor-driven propelling device for toys showing my design;
FIGURE 2 is a rear elevational view thereof;
FIGURE 3 is a right side elevational view thereof;
FIGURE 4 is a left side elevational view thereof;
FIGURE 5 is a top plan view thereof; and
FIGURE 6 is a bottom plan view thereof.

I claim:

I claim the ornamental design for a motor-driven propelling device for toys or similar article, as shown.
